CLAIM

The ornamental design for a panoramic videoconferencing system, as shown.

DESCRIPTION

FIG. 1 is a perspective view showing the top, front and right side of a panoramic videoconferencing system according to my new design;

FIG. 2 is a top view of the panoramic videoconferencing system shown in FIG. 1;

FIG. 3 is a front view of the panoramic videoconferencing system shown in FIG. 1;

FIG. 4 is a rear view of the panoramic videoconferencing system shown in FIG. 1;

FIG. 5 is a left side view of the panoramic videoconferencing system shown in FIG. 1; and,

FIG. 6 is a right side view of the panoramic videoconferencing system shown in FIG. 1.
